(57) **CLAIM**

I claim the ornamental design for a column forming block, as shown.

DESCRIPTION

FIG. 1 is a perspective view of a column forming block showing my new design.

FIG. 2 is another perspective view thereof.

FIG. 3 is a front view thereof.

FIG. 4 is a rear view thereof.

FIG. 5 is a side view thereof.

FIG. 6 is another side view thereof.

FIG. 7 is a top view thereof; and,

FIG. 8 is a bottom view thereof.

The broken lines appearing in the figures are not intended to form part of the claimed design and are provided for illustrating purposes only.
